F. S. CRAMER.
VACUUM CLEANER.
APPLICATION FILED JULY 6, 1911.

1,045,950.

Patented Dec. 3, 1912.

UNITED STATES PATENT OFFICE.

FRED S. CRAMER, OF JUNCTION CITY, KANSAS.
Inventor.

VACUUM-CLEANER.

1,045,950. Specification of Letters Patent. Patented Dec. 3, 1912.
Application filed July 6, 1911. Serial No. 637,051.

To all whom it may concern:

Be it known that I, FRED S. CRAMER, a citizen of the United States, residing at Junction City, in the county of Geary and

5 State of Kansas, have invented a new and useful Vacuum-Cleaner, of which the following is a specification.

This invention relates to vacuum cleaners of that type adapted to be operated by hand, 10 one of the objects of the invention being to provide a simple and efficient device of this type which can be easily operated and which is comparatively cheap to manufacture.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed can be made within the scope of what is claimed without departing from the spirit of the invention.

In the accompanying drawings, the preferred form of the invention has been shown.

In said drawings:—Figure 1 is a perspective view of the machine. Fig. 2 is an enlarged view partly in transverse section and partly in elevation. Fig. 3 is an enlarged 30 longitudinal section through the adjustable support. Fig. 4 is a transverse section through a portion of the bottom of the casing.

Referring to the figures by characters of reference A designates a casing preferably made up of oppositely disposed frusto-conical sections 1 and 2, each of these sections having an annular flange 3 at its large or open side. These flanges are adapted to be 35 bolted or otherwise secured upon opposite faces of the marginal portion of a diaphragm 4 preferably made of sheep skin and to the middle portion of which are attached plates 5, these plates being arranged 40 on opposed faces of the diaphragm. A packing gland 6 is located at the center of the side of section 2 of the casing and a rod 7 is mounted to slide therein, one end of the rod being connected to the center portions 45 of the plates 5 and diaphragm 4 while the other or outer end portion of this rod is pivotally connected to a lever 8 fulcrumed, as at 9, upon a bracket 10 extending laterally from the casing section 2. Lever 8 constitutes one of the handles of the machine. 50 The other handle, has been indicated at 11

and is fixedly connected to the outer side of the section 1 of casing A, said handles being preferably mounted within sleeves 12 extending from said sections.

60 Valve casings 13 are formed upon the sections 1 and 2 adjacent the bracket 10 and the lower end of handle 11 and communicate with the interior of casing A through ports 14. Valves 15 normally close these ports. 65 Downwardly converging pipes 16 extend from the respective casings 13 and are connected to a head 17. This head is detachably engaged by the tubular stem 18 of a nozzle 19 and the nozzle may be of any desired type, this being dependent upon the work to be done. Cleanout openings 20 are formed in the lower portions of the sections 1 and 2 and are normally closed by screw caps 21.

75 Valve casings 22 are secured upon the sections 1 and 2 at points diametrically opposite the casings 13 and each of these casings 22 communicates with the interior of casing A through a port 23 normally closed by a valve 24. Outlet pipes 25 extend from the casing 22 and open into a coupling 26 from which projects a tubular outlet stem 27. A bag 28 of any suitable coarse fabric is adapted to be secured about the stem 27 by gathering the open end thereof and tying it to the stem by means of a cord or the like. The bag may be supported between the handle 11 and lever 8 by cords, such as indicated 80 at 29, said bag being thus held out of contact 85 with the surface being cleaned.

A hanger 30 is fixedly connected to the rear portion of casing A and is adjustably engaged by a standard 31 the lower forked end 32 of which has a supporting wheel 33 90 journaled therein.

When it is desired to use the cleaner the standard 31 is first adjusted along the hanger 30 so that wheel 33 will support the handle 11 and lever 8 at any desired angle. 100 The cleaner can therefore be used conveniently by persons of different heights. After the parts have thus been adjusted the dust collector or bag 28 is secured between handle 11 and lever 8 and with its open end about the outlet stem 27. The machine is then reciprocated over the surface to be cleaned, the nozzle 19 being held close to said surface. When the machine is being pushed forward the natural tendency of the 105 arms of the operator is to move toward each other. This will, obviously, result in 110

lever 8 being swung toward handle 11. Rod 7 will therefore push on the diaphragm 4 and create a suction through nozzle 19, stem 18 and one of the pipes 16 to the interior of casing section 2. At the same time, a portion of the air contained within the casing 1 will be expelled through the pipe 25 communicating with said section and thence to the stem 27 and the dust receiver 28. When 10 the machine is moved toward the operator the tendency of the arms is to move apart. This will result in lever 8 being swung away from the handle 11 and rod 7 will therefore pull on the diaphragm 4 and create a suction through the nozzle 19 into the section 1 while the dust laden air previously drawn into the section 2 will be expelled through pipe 25 into the dust receiver 28.

From the foregoing it will be apparent 20 that the machine can be easily cleaned without requiring any unnatural or excessively tiring movements of the arms, the movement of the machine and the actuation of the diaphragm being effected solely by reciprocating 25 the machine over the surface to be cleaned.

It will be apparent that bag 28 can be easily removed when filled and as this bag 30 is made of a fabric, air discharged thereinto will be promptly dissipated, while the dust will be retained within the bag. Should any dust collect within either of

the sections of casing A, it can be easily removed by opening the cleanout openings 20.

By supporting the bag 28 from the fixed 35 handle 11 and the movable handle 8, it will be seen that, during the operation of the pump, the bag will be thoroughly agitated, thus preventing dust therein from becoming caked on the inner surface of the bag and 40 interfering with the escape of air through the fabric.

The machine herein described is very simple in construction and is easy to operate and is advantageous because of its simplicity 45 and consequent cheapness.

What is claimed is:—

A vacuum cleaner including a pump, an outlet stem extending therefrom, a handle fixed relative to the pump, an operating 50 handle movably connected thereto, and a fabric dust receiver secured about the outlet stem and to the handles, the movable handle constituting means for agitating the receiver during the discharge thereinto from 55 the pump.

In testimony that I claim the foregoing as my own, I have hereto affixed my signature in the presence of two witnesses.

FRED S. CRAMER.
